(57) **CLAIM**

The ornamental design for phototherapy goggles, as shown and described.

DESCRIPTION

FIG. 1 is a front elevational view of an embodiment of phototherapy goggles according to our new design;

FIG. 2 is a rear elevational view of the phototherapy goggles shown in FIG. 1;

FIG. 3 is a top plan view of the phototherapy goggles shown in FIG. 1;

FIG. 4 is a bottom plan view of the phototherapy goggles shown in FIG. 1;

FIG. 5 is a left elevational view of the phototherapy goggles shown in FIG. 1; and,

FIG. 6 is a right elevational view of the phototherapy goggles shown in FIG. 1.

The portions drawn in broken lines are shown for illustrative purposes only and form no part of the claimed design.
